UNITED STATES PATENT OFFICE.

CASPAR WISTAR MILLER, OF WALLINGFORD, PENNSYLVANIA.

AIR-GAS APPARATUS.

SPECIFICATION forming part of Letters Patent No. 660,916, dated October 30, 1900.

Application filed June 7, 1899. Serial No. 719,681. (No model.)

To all whom it may concern:

Be it known that I, CASPAR WISTAR MILLER, a citizen of the United States, and a resident of Wallingford, Delaware county, Pennsylvania, have invented certain Improvements in Air-Gas Apparatus, of which the following is a specification.

My invention consists of certain improvements in mechanism for actuating the water-valve of an air-gas apparatus.

The object of my invention is to so construct the mechanism that the valve will be gradually moved during the fall of the moving section of the air-reservoir, so that the work of moving it may be distributed steadily or uniformly throughout the entire fall of the gas-holder, whereby the pressure in the said gas-holder may remain constant.

In the accompanying drawings, Figure 1 is a side view of sufficient of an air-gas apparatus to illustrate my invention. Fig. 2 is an end view of Fig. 1, partly in section. Fig. 3 is a side view, drawn to a reduced scale, showing the air-reservoir in full; and Fig. 4 is a view of a modification of my invention. Figs. 5 and 6 are vertical sectional details of the valves shown in Fig. 1.

While my invention is adapted to any form of air-gas apparatus in which the air-reservoir has a moving part controlled by a fluid-pressure cylinder and piston, I will describe my invention in connection with one of the well-known forms of gas apparatus to which I have applied my improvements.

A is the fixed portion of the air-reservoir, supported on suitable standards A'.

A² is the movable portion, adapted to work within the fixed portion A, as shown in Fig. 3.

B is the carbureter. In the present instance this carbureter is a horizontal cylinder connected to the air-reservoir A through the pipe b, valve-casing C, and pipe c'.

c is the air-inlet, through which air is admitted to the air-reservoir A through a valve-casing C.

The check-valve o, Fig. 5, in this casing is so arranged that it allows air to be drawn into the reservoir on the upstroke of the movable section A², the valve p being closed and cutting off communication with the carbureter B. On the downstroke o will be closed and air will flow through p into B.

G is a shaft adapted to suitable bearings on

the frame of the machine, and on this shaft is a wheel g, from which is suspended a weight g² by a chain g', and also on the shaft are two chain-wheels g³, attached to which are chains a, connected to the moving section of the air-reservoir. On the shaft G is a pulley h, and in the carbureter B is a shaft b', having a pulley b². The shaft b' is driven from the shaft G by a belt h'.

D is a fluid-pressure cylinder.

E is a piston-rod extending into the cylinder and connected at its upper end to the moving section A² of the reservoir. The lower end of this piston-rod is not attached to the piston, but is in contact with it only when the piston is raising the moving section of the reservoir.

F is the valve controlling the admission of fluid to the cylinder D.

f' is the fluid-inlet pipe.

f' is the outlet-pipe, and m, m', n', r, and r' are passages connecting the various parts of the valve F.

In the base of the cylinder D is a casing in which is an auxiliary valve having three pistons fixed to one spindle and constructed to rise and fall therein. Ports connect the center of this casing through the annular recess r with the interior of the cylinder D, and other ports somewhat above these open to the inlet f and through n' to the valve F, respectively. A passage r' connects the upper part of the casing with the upper part of F, while a similar passage n leads from a point below the center of said casing to the exhaust f'. A relatively small passage m connects the lowest part of the casing through m' with F at a point between the exhaust and the passage n'. The spindle f² of the valve F has two pistons on it, which when it is at the lowest point of its stroke are situated just below the passages m' and r', respectively, and at its highest point are just above these passages.

f² is the valve-rod, connected to the short arm i' of the lever I, pivoted at i to a bracket on an extension of the cylinder D. i² is the long arm of the lever, which is engaged by the piston of the cylinder D on its upward stroke, so as to cut off the supply of water and open the cylinder to waste.

The above-described apparatus is found on

one of the well-known air-gas machines, and I lay no claim whatever to this construction.

Heretofore in air-gas apparatus of this type the valve was shifted only during the last portion of the downstroke of the moving portion of the air-reservoir. Consequently there was more or less unevenness in the pressure and a certain amount of flickering, blowing, and waste of gas at certain intervals, which is one of the great objections to isolated air-gas apparatus as at present designed. By my invention I entirely overcome this objection and so arrange the parts that there will be an even pressure throughout and the change is hardly perceptible. This I attain by connecting the long arm of the lever I to the moving portion of the air-reservoir or to apparatus connected therewith that the movement of the valve will be coincident with the movement of the moving section of the air-reservoir. In the present instance I attain this object in the following manner: On the shaft G, I secure a flanged scroll K. This scroll may be made in two parts and clamped to the shaft, the same as a two-part pulley, and the form of the scroll will depend upon the movement of the moving section of the air-reservoir and upon the connections and the length of the long arm of the lever I. I preferably extend the flanges of the scroll down onto the shaft. Secured to the end of the arm i^2 of the lever I is a chain k, which passes around chain-wheels k' k'' and is attached to the highest portion of the scroll, as shown in Fig. 2, by a pin or other device. Interposed between the chain k and the lever I is a spring k^3 . This spring may be placed at any point throughout the length of the chain. In Fig. 4 I have shown the chain connected directly to the lever and the spring mounted between the wheel k' and the frame. The purpose of this spring is to provide means for moving the valve F during part of its stroke by energy taken directly from the piston and stored in the spring, thus reducing the distance through which it must be subsequently moved by the rotation of the shaft and also to keep the parts taut, thus taking up all unnecessary slack.

It will be understood that in addition to the parts shown in the drawings a machine of the type described has a second air-reservoir with a movable section situated near the one illustrated at A and connected to the carbureter and to the gas-supply main. The movable section of this reservoir is weighted, so that the pressure of the gas in the main is very slightly below that of the air supplied to the carbureter from the reservoir A.

The operation of the device is as follows: As shown in the drawings, the moving portion of the air-reservoir is in the elevated position, and the flow of water to the cylinder is shut off and the exhaust is open. If gas is being utilized, then the air will pass from the reservoir A through the pipe c', valve-casing C, and pipe b to the carbureter B, and as the air escapes the weight g^2 will cause the mov-

ing section of the reservoir to be drawn down, and as the shaft G is turned the chain k will be wound upon the scroll K. The air entering the carbureter has added to it the necessary quantity of combustible illuminating fluid, after which it passes as gas to the second reservoir and into the gas-main. (Not shown.) During the time that the movable section A² is being raised the pressure in the mains is kept constant by the weighted movable section of the second reservoir. The first movement of the lever I, however, will be caused by the contraction of the spring k^3 , as the parts are so set that the last upward movement of the lever I will expand the spring, and as the piston is not attached to the piston-rod the piston will fall back by contraction of the spring as soon as the water 85 below the piston is allowed to escape. After the spring is contracted then the coiling of the chain upon the scroll will draw down the long arm of the lever I and will gradually shift the valve in the valve-casing F. This 90 movement is continuous throughout the travel of the moving portion of the reservoir until the water-pressure is sufficient to move the piston within the cylinder, when the operation will be reversed. In order to obtain 95 the best mechanical advantage, the last part of the winding may be done directly on the shaft. If this arrangement be adopted, the flanges of the scroll should be continued beyond the bottom, as shown in the drawings, 100 so that the chain may always follow a definite course. I prefer to allow about the last eighth of the total length of the chain to be wound on the shaft direct, the other seven-eighths being wound on the scroll. When the moving 105 section of the reservoir is raised by the fluid entering the cylinder D, the lever I remains in the position in which it was set by the chain until actuated by the piston near the end of the upward stroke. In the meantime 110 the shaft G has been revolved in the opposite direction, so that the chain will become slack; but as soon as the piston strikes the lever I this slack is immediately taken up by the movement of the lever, and the continued 115 movement of the piston places the spring k^3 under tension. The valve is then shifted and the operation is repeated.

Two valves may be used—one an inlet-valve and the other an outlet-valve—in place of the 120 single valve shown and described.

I claim as my invention—

1. The combination in an air-gas apparatus, of the air-reservoir having a moving section, a cylinder, a piston in the cylinder 125 adapted to raise the moving section of the air-reservoir, a valve controlling the admission of fluid to and exhaust from the cylinder, a lever connected to the valve, a driven shaft, mechanism connecting said shaft with the 130 moving section of the reservoir and a scroll on the shaft and a chain adapted to the scroll and connected to the lever, substantially as described.

2. The combination in an air-gas apparatus, of the reservoir having a moving section, a cylinder, a piston in the cylinder connected to the moving section of the air-reservoir, a 5 valve controlling the admission of fluid to and exhaust from the cylinder, a lever connected to the valve, a shaft turned in unison with the movement of the moving section of the air-reservoir, a scroll on the shaft, and a 10 chain secured to the highest portion of the scroll and to the long arm of the lever and passing around pulleys so that the lever will be drawn down as the air is exhausted from the reservoir, substantially as described.
- 15 3. The combination in an air-gas apparatus, of the air-reservoir having a moving section, a cylinder, a piston within the cylinder, a rod extending from the moving section of the air-reservoir to the piston, a valve controlling the admission of fluid to and exhaust 20 from the cylinder, a lever connected to the valve, a shaft connected to the moving sec-
- tion of the reservoir, a scroll on the shaft, a chain connected to the scroll and to the lever, and an interposed spring, substantially as 25 and for the purpose set forth.
4. The combination in an air-gas apparatus, of an air-reservoir having a moving section, a cylinder, a piston therein, a rod extending from the moving section of the reservoir to the piston, a valve governing the flow of fluid to the cylinder, a lever connected to the valve, and a spring attached to the lever so that when the lever is raised by the piston the spring will be under tension, and 30 the spring on its recoil will shift the valve, substantially as described.
